Attorney

UNITED STATES PATENT OFFICE.

JOEL T. HART, OF FOSTER, MISSOURI.

VEHICLE-HUB.

SPECIFICATION forming part of Letters Patent No. 446,347, dated February 10, 1891.

Application filed June 30, 1890. Serial No. 357,250. (No model.)

To all whom it may concern:

Be it known that I, JOEL T. HART, a citizen of the United States, residing at Foster, in the county of Bates and State of Missouri, have 5 invented certain new and useful Improvements in Vehicle-Hubs; and I do hereby declare that the following is a full, clear, and exact description of the same, reference being had to the annexed drawings, making a 10 part of this specification, and to the letters of reference marked thereon.

This invention relates to certain new and useful improvements in vehicle-wheels; and it has for its object, among others, to provide 15 an improved wheel and hub in which the parts shall be separable and adjustable, readily assembled or separated when occasion may require, and which in use shall constitute a strong and durable wheel.

20 Other objects and advantages of the invention will hereinafter appear, and the novel features thereof will be specifically defined by the appended claims.

The invention is clearly illustrated in the 25 accompanying drawings, which, with the letters of reference marked thereon, form a part of this specification, and in which--

Figure 1 is a longitudinal section through a wheel constructed in accordance with my 30 invention. Fig. 2 is an end view with the washer and cap removed. Fig. 3 is a face view of the washer removed, looking at the inner face. Fig. 4 is a side view of the box removed. Fig. 5 is a like view of the cap.

35 Like letters of reference indicate like parts throughout the several views.

Referring now to the details of the drawings by letter, A designates the box, which is exteriorly threaded, being preferably provided with right and left screw-threads, as 40 shown in Fig. 4, although the threads may all extend in one direction, as shown in Fig. 1. The right and left threads are preferred, however, as it prevents the parts from unscrewing by contact with the collar or shoulder and the nut on the axle.

B is one-half of the hub. It is formed with interior threads to engage the threads of the box, and upon its inner face is formed with

spoke-sockets *a*, as seen in Fig. 2, the V-shaped portions *b* forming said sockets being of less length than the width of the tenon end of the spokes, as shown in Fig. 1, so as to allow for tightening up of the parts when desired, which could not be accomplished so well 55 if the said portions extended the full length of the space, as will be readily understood.

C are the spokes, having tenon ends fitting the spoke-sockets, with their inner ends bearing against the box, as seen in Fig. 2, the shoulders *c* conforming to the curvature of the outer face of the portions *b*, as seen in the same figure.

D is a washer, which is slipped on over the box from the opposite side of the spokes, and 65 it is formed upon its inner face with pins or projections *d*, adapted to enter openings or sockets *e* in the center of the spokes, as seen in Figs. 1 and 2, and hold them from displacement or movement.

70 E is the cap, internally threaded to engage the threads of the box, as shown in Fig. 1, and shaped to complete the contour of the half of the hub. It is formed with a polygonal portion *f* or other provision for the reception 75 of a wrench or other tool by which it may be screwed up. It bears against the washer D, and when screwed up presses the same against the spokes and forces the pins *d* into the sockets in the spokes. The portion B of the 80 hub is also provided with polygonal portion or other provisions for screwing it up, and both the portion B and cap E are preferably secured to the box by screws or other analogous devices *g*, as shown in Fig. 1.

85 What I claim as new is--

1. The combination, with the threaded box, the portion B, formed with spoke-sockets, the V-shaped portions *b*, forming said spoke-sockets, being of less length than the width of the tenon end of the spoke, and the spokes each provided with a socket, of the washer loosely sleeved upon the box and formed upon its inner face with projections engaging the sockets of the spokes, and the cap threaded on the 90 box and bearing against the washer, substantially as specified.

2. The combination, with the box provided

with right and left threads, of the portion B, threaded on the box and formed with spoke-sockets, the washer loosely sleeved upon the box and formed with projections to engage 5 sockets in the spokes, and the threaded cap bearing against the washer, substantially as and for the purpose specified.

In testimony that I claim the above I have hereunto subscribed my name in the presence of two witnesses.

JOEL T. HART.
